UNITED STATES PATENT OFFICE.

HENRY HUNT, OF GREENVILLE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 13,812, dated March 27, 1883.

Application filed January 25, 1883. Term of patent 3½ years.

To all whom it may concern:

Be it known that I, HENRY HUNT, of Greenville, in the county of Hudson and State of New Jersey, have invented a new and original Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

A plain ground is loosely strewn with various disconnected figures of irregular and fan-

ciful shapes, prominent among which are the figures A, B, C, D, E, F, G, and H, which are clearly shown in the photograph. In the spaces between these figures are various smaller figures, fanciful leaf sprays, and bud-like forms, all as shown in the accompanying photograph. The design presents an open appearance.

I claim—

The design for a carpet, substantially as shown and described.

HENRY HUNT.
